PNEUMATIC POWER DEVICE

Erich David, United States Army

Application April 2, 1942, Serial No. 437,450

2 Claims. (Cl. 254—93)

My invention relates to mechanical devices for exerting great pressure, lifting or moving heavy or light bodies, and has among its objects and advantages the provision of an improved pneumatic pressure device particularly suitable for jack purposes, wherein novel means are incorporated to provide a pressure-tight construction operating in an efficient manner over long periods of time notwithstanding wear on the relatively movable parts.

In the accompanying drawing:

Figure 1 is a vertical sectional view of the jack; and

Figure 2 is a sectional view taken along the line 2—2 of Figure 1.

The jack comprises a cylinder 90 having its lower end threadedly connected in a hollow cylindrical base 92, as at 92^a. The base 92 is provided between its ends with a horizontal wall 92^b coacting with the cylinder 90 and a piston 96 to provide a chamber for the reception of an extensible enclosure or inflatable bladder 94, which may comprise rubber. Lifting power for the piston 96 is derived from the introduction of air under pressure inside the bladder 94 to cause the bladder to expand and lift the piston. To the bottom end of the piston 96 is secured a soft leather washer 98, as by screws 98^a, which washer provides a cushion for the bladder 94. I prefer to shape the bladder-engaging face of the washer 98 with a gentle concaved face 98^b. The piston 96 is slightly smaller diametrically than the corresponding inner dimension of the cylinder 90. The washer 98 contacts with the side wall of the cylinder 90 and holds the piston 96 against lateral play and maintains the upper end of the bladder 94 out of contact with the inner wall of the cylinder.

A tubular elbow 64 is secured to the bottom end of the bladder 94 through the medium of a flange 66 engaging the inner face of the bladder and a nut 68 threadedly connected with the elbow 64 to press a washer 70 against the bladder and clamp the latter between the washer and the flange. The central portion of the wall 92^b is depressed to provide a recess for the reception of the nut 68 and the washer 70. To the outer end of the elbow 64 is connected a hose 72 having a control valve 74 interposed therein. This valve includes a housing 76 having a vent opening 78 and a rotary plug 80 provided with bores 82 and 84. A handle, not shown, is attached to the plug to facilitates rotation thereof.

Figure 1 illustrates the valve plug 80 adjusted so as to pass air under pressure into the bladder 94. Rotation of the plug 80 in a clockwise direction to bring the bore 82 into communication with the opening 78 and the section 88 of the hose 72 cuts off the supply of air under pressure

and vents the bladder to the atmosphere so that the piston 96 may descend.

To the piston 96 is fixedly secured an elevating shaft 100 slidably guided in a bearing 102 on a plate 104 threadedly connected at 106 with the upper end of the cylinder 90. This cylinder is constricted at its upper end to provide a shoulder 108 to limit the upward movement of the piston 96 when the bladder 94 is inflated a predetermined amount.

Between the piston 96 and the cover 104 is interposed a compression spring 110 to cause the piston to descend in the cylinder 90 when the air pressure is released from the bladder 94. An extension screw 112 is threaded into a longitudinal bore 114 in the shaft 100, which screw is provided with a lifting head 114. Thus the screw 112 may be adjusted to afford a greater or lesser effective reach for the jack. A hose 118 connected to the control valve 74 may be provided with a conventional inner tube inflation valve at its end for connection with an ordinary tire pump.

Without further elaboration, the foregoing will so fully illustrate my invention, that others may, by applying current knowledge, readily adapt the same for use under various conditions of service.

I claim:

1. A pneumatic jack comprising a hollow cylindrical base provided between its ends with a wall, a cylinder having its lower end positioned in and secured to the base above said wall, a piston slidably mounted in the cylinder and carrying work engaging means, the piston being slightly smaller diametrically than the corresponding inner dimension of the cylinder, a bladder within the cylinder below the piston, a washer of softer material located between the piston and bladder and contacting with the inner wall of the cylinder and embracing the upper end portion of the bladder, the wall of the base being provided with a central depression, an inflating tube for the bladder passing through the side wall of the base and through the depressed portion of the wall of the base, and means for securing the tube to the lower end of the bladder, said means fitting in said depression.

2. A pneumatic jack such as claimed in claim 1, wherein the upper portion of the cylinder is slightly reduced to provide an inner shoulder adapted to limit the upward movement of the piston, wherein the upper end of the cylinder is closed by a plate provided at its center with inner and outer bearing bosses, wherein the work engaging means of the piston passes through said bosses, and wherein the piston is constantly urged downwardly by a coil spring surrounding said means and bearing against the piston and the plates closing the upper end of the cylinder, the upper end of the spring surrounding said inner boss.

ERICH DAVID.
